ROOFING TILE

Wilhelm Ludowici, Jockgrim/Pfalz, Germany

Application April 3, 1933, Serial No. 664,218
In Germany July 4, 1932

12 Claims. (Cl. 108—10)

This invention relates to an improved roofing tile, and has for its object to provide a roofing tile with special dovetailing so that a roof covered with these tiles is rendered tight against water, dirt and light, and moreover such a tile whereby inaccuracy in the placing of the laths on which the tiles are hung will not affect the tightness of the roof.

The tiles are hung side by side in rows and one under the other, so that in every set of four tiles there will be four corners overlapping, and according to the invention means are provided whereby at such a meeting of the four corners—hereinafter termed a "4 tile corner"—one tile shall always overlap another and that the overlapping tile shall dovetail with at least one tile below. Furthermore, the water running down the water trough between two adjacent tiles is made to run off outside the "4 tile corner". In carrying out this invention the water is made to run off as far as possible above the "4 tile corner" in such a way that the water passes under the curvature of the overlapping tile out of the water trough on to the free tile surface. At the same time the running off edge in the dovetailing is preferably made with a sharp edge to allow a more free run for the water, and to make the separation as efficient as possible and to prevent as far as possible the snow, dust etc., from striking through. The lower opening of the dovetailing at the "4 tile corner" is arranged so that it leads out in the opposite direction to the covering.

The actual separation of the dovetailing against the water is arranged for in the simplest way by a cross rib in the side dovetailing, which rests against a similar cross rib bent sideways in a rib provided on the underside of the tile above, which rib fits for the whole of its length inside the side dovetailing and has a gap to take the cross rib.

The important advantage of this complete separation lies in the main in the fact that it permits the construction of the "4 tile corner" without regard to the run of the water and so that it is safe against drifting snow, dirt, and is light tight.

The invention will be more clearly understood with reference to the accompanying drawings which illustrate by way of example two forms of the invention.

In the drawings, wherein like references denote the same or similar parts—

Fig. 1 shows a top view of a tile in accordance

Fig. 2 is a view of Fig. 1 when turned over about its right hand longitudinal edge, and shows the underneath of the tile;

Fig. 3 is a cross section along the line A—B of Fig. 1;

Fig. 4 is a cross section along the line E—F of Fig. 1;

Fig. 5 is a right hand side elevation of Fig. 2;

Fig. 6 is a longitudinal cross section of Fig. 1 along the line C—D;

Fig. 7 is a cross section through the "4 tile corner" along a line parallel to the eaves of the roof;

Fig. 8 is a view from underneath of the two upper tiles of a "4 tile corner";

Fig. 9 is a top view of a tile according to the invention with an alternative form of dovetailing;

Fig. 10 is a section along the line 10—10 of Fig. 9; and

Fig. 11 is a perspective view of part of the "4 tile corner" with the uppermost tile removed.

The dovetailing of a tile P comprises ribs a and b on the side edge, i. e. left hand edge of Fig. 1, of the upper surface, and continued along the upper edge at a' and b' where they form the upper dovetailing. On the under surface of the tile, i. e. at the right hand side of Fig. 1 and seen on the left hand side of Fig. 2, is a corresponding rib c, which, when the tiles are laid together, fits into the groove between the ribs a and b of the adjacent underneath tile. Parallel with the rib c is a rib e (Figs. 2 and 7) which is sharp edged and extends along the length of the tile to form the groove d with which the rib a on the overlapping tile co-operates as shown in Fig. 7. Along the left hand edge of Fig. 2, i. e. on the underneath of the tile, is a rib f which is continued along the lower edge as f' and forms, when the tile is laid, a complete enclosure.

Also on the underside of the tile at the bottom end is a cross rib g (Figs. 2, 5, and 6) having an offset g' against which the groove d and its ribs c and e terminate.

At the top end of the tile also on the underside thereof, is a transverse projection h (Figs. 2, 5, and 6) by which the tile is hung, an eyelet h' near the lower end of the tile being provided for fastening the tile to the laths. Finally, there are at the lower right edge (see Fig. 2) recesses and means for dovetailing the "4 tile corner", as hereafter described.

The separation of the watercourse on the side dovetailing and the leading of the water away from the "4 tile corner" is effected by means of the rib i (Figs. 1 and 6) across the groove formed

side of the top face of said surface, spaced ribs along the opposite longitudinal side of said top face and continued along one transverse side of the tile, corresponding ribs spaced apart along the opposite sides of the underneath face of said main surface whereby four of such tiles may be laid together in overlapping relation, oppositely inclined cross ribs connecting the spaced longitudinal ribs on both faces of the tile, the cross 5 rib on the top face extending from one edge of a slot in the inner longitudinal rib of said top face and the cross rib on the underneath face extending from the opposite edge of a corresponding slot in the inner longitudinal rib of the underneath face, a curved portion between the inner longitudinal and transverse ribs on the top surface, the inner rib on the under face being offset outwardly adjacent the inner longitudinal rib on the under face, said longitudinal rib extending to said offset 10 portion, the end of the transverse rib on the under face being adapted to abut against said curved portion on the tile next below.

7. A roofing tile according to claim 5 including a raised water-runway between the spaced longitudinal ribs on the top face and a sharp edged outlet to said runway leading through said slot in the inner longitudinal rib of said top face to the main surface of the tile.

8. A roofing tile according to claim 5, including a raised water-runway between the spaced longitudinal ribs on the top face, and a stepped outlet to said runway leading through said slot in the inner longitudinal rib to the main surface of the tile.

35 9. A roofing tile according to claim 5, including a raised water-runway between the spaced longitudinal ribs on the top face, and a stepped, sharp-edged outlet to said runway leading through said slot in the inner longitudinal rib to the main surface of the tile.

40 10. A roofing tile according to claim 5, having recesses in the inner transverse ribs on both faces of the tile, the recess in the rib on the top face being disposed at the end of the rib, and the recess in the rib on the underneath face being disposed adjacent the inner longitudinal rib of said underneath face, the said tile including projections adjacent the outer end of the inner transverse rib of the underneath face for co-operating with said recesses of adjacent tiles when laid, whereby adjustment is provided for.

45 11. A roofing tile comprising a main surface with a curved raised portion along one longitudinal side of the top face of said surface, spaced ribs along the opposite longitudinal side of said top face and continued along one transverse side

of the tile, corresponding ribs spaced apart along the opposite sides of the underneath face of said main surface whereby four of such tiles may be laid together in overlapping relation, cross ribs connecting the spaced longitudinal ribs on both faces of the tile, the cross rib on the top face extending from one edge of a slot in the inner longitudinal rib of said top face and the cross rib on the underneath face extending from the opposite edge of a corresponding slot in the inner longitudinal rib of the underneath face, the inner transverse rib on the underface being offset outwardly at the end thereof adjacent the corresponding longitudinal rib, and a rib-like projection at the other end of the last mentioned inner transverse rib, said rib like projection being adapted to co-operate with the offset portion of the inner transverse rib on the under face of the adjoining tile so as to continue said inner transverse rib in a straight line.

50 12. A roofing tile comprising a main surface with a curved raised portion along one longitudinal side of the top face of said surface, spaced ribs along the opposite longitudinal side of said top face and continued along one transverse side of the tile, corresponding ribs spaced apart along the opposite sides of the underneath face of said main surface whereby four of such tiles may be laid together in overlapping relation, cross ribs connecting the spaced longitudinal ribs on both faces of the tile, the cross rib on the top face extending from one edge of a slot in the inner longitudinal rib of said top face and the cross rib on the underneath face extending from the opposite edge of a corresponding slot in the inner longitudinal rib of the underneath face, a curved portion between the inner longitudinal and transverse ribs on the top face, the inner transverse rib on the top face having an inwardly directed offset at its outer end, an end piece on the corner of the tile diagonally opposite said offset, said end piece being of such a shape as to close completely over the corresponding offset on the tile next below, the inner transverse rib on the underface adjacent the corresponding inner longitudinal rib, said longitudinal rib extending to said last mentioned offset, the opposite end of the transverse rib on the underface being adapted to abut against the said curved portion of the tile next below, and a rib like projection adjacent the said opposite end of said inner transverse rib, said rib-like projection being adapted to co-operate with the offset of the inner transverse rib of the adjoining tile so as to continue said inner transverse rib in a straight line.
